PUMP LOCK

Robert St. J. Orr, San Francisco, Calif.

Application December 18, 1944, Serial No. 568,688

3 Claims. (Cl. 103—202)

1

This invention relates to a pump lock and has for its main object the provision of a simple, quick releasable and reliable means for locking the pump cylinder and plunger that is reciprocable therein in telescopically collapsed position against accidental withdrawal of the plunger.

The particular type of pump with which this invention is concerned is commonly used by forest service men in the fighting of fires, in which an inner cylinder carrying a handle and nozzle at one end, is reciprocable within an outer cylinder that is connected by a hose with a source of liquid, such liquid generally being in a tank carried by knapsack straps on the back of the operator. When not in actual use, the pump, which is ordinarily between two and three feet in length, may be releasably secured on top of the tank behind the back of the operator and in a position extending horizontally across the tank.

In the carrying of the pump on the tank, considerable difficulty has been experienced by reason of the tendency of the plunger to move gradually outwardly of the pump cylinder to its extended position. Strenuous activity of the wearer may expedite this movement. One result of such movement of which the operator may be unaware is that the pump is constantly in danger of being damaged and in many instances pumps have been completely incapacitated and rendered useless at critical times. Also, on occasions, the operators have been seriously injured due to unexpected catching of the extended plunger on trees, shrubs, boulders or on the sides of cliffs.

The problem of overcoming the above objections involves many considerations, principal among which are reliability, durability, ease of manipulation and simplicity.

The instant invention solves said objections and in addition to the above-mentioned requirements it is economical to make and does not interfere in any degree with the operation of the pump nor does it, by overcoming one hazard, give rise to another.

Other objects and advantages will appear in the drawings and description.

In the drawings,

Fig. 1 is an elevational view of a pump tank with the pump releasably secured thereon in inoperative position and with the pump collapsed.

Fig. 2 is an enlarged part-sectional and part-elevational view of the handle, nozzle and the means for releasably locking the pump cylinder and plunger together. The cylinder and plunger are shown unlocked and separated in this view.

2

Fig. 3 is a sectional view taken along line 3—3 of Fig. 2.

Fig. 4 is a sectional view taken along line 4—4 of Fig. 2.

5 Fig. 5 is a fragmentary elevational view of the locking elements of the plunger and cylinder in locked position.

In detail, the pump of this invention is the type generally called "knapsack pump-tanks" or "back-pumps," and which have been employed for about twenty-five years in the control of grass, brush and forest fires by the United States Forest Service and other agencies. Also such pumps are adapted to use sprays in pest control. The pump itself in each unit is tubular and is generally releasably held in generally U-shaped spring clips 1 on top of a knapsack tank 2 (Fig. 1), the latter having straps 3 for securing of the tank on the back of the operator. A flexible hose 4 connects one end of the pump with the tank. The contents of the tank may be any desired liquid according to the purpose for which it is used. As a common size of these pumps is capable of throwing a stream about forty feet vertically or horizontally, it is seen that the unit is very efficient in the suppression and control of incipient fires, spot fires, mop-up work, snag fires, pole-line fires, etc.

30 The pump itself comprises an outer pump cylinder 5 having a conventional hose connection at one end for securing in the end of the hose 4 that is opposite the end of the latter that is secured to tank 2. This hose is of sufficient length so that the operator may detach the pump from the tank and swing it into pumping position at either side of the body without removing the tank from his back.

40 A tubular plunger 6 is reciprocable within the cylinder 5, and projects from the end of said cylinder that is opposite hose 4 when said plunger is at the limit of its stroke inwardly into cylinder 5, which is the collapsed position of the pump as distinguished from its extended position in which the plunger is at the limit of its outward stroke.

45 A tubular handle 7 coaxial with plunger 6 encloses the projecting end portion of the latter. Said handle is secured to said projecting end by any suitable means and a relatively short end of the plunger tube projects from the outer end of the handle, or the end that is opposite cylinder 5, for securing of a nozzle 8 to such end.

50 The overall length of the pump from the nozzle to hose 4 when the pump is in collapsed position on the tank 2 is preferably about 26 inches and

as it is carried horizontally on the tank so that the latter is centrally between its ends, there is very little projection outwardly of opposite sides of the operator when the pump and tank are being carried.

The pump elements above described are conventional. The present invention is concerned with means in such pump for securing the plunger in collapsed position while the pump is being carried so that the handle end will not work itself out, as heretofore, until the plunger is partially or wholly in extended position. Figs. 2 to 5 more specifically illustrate one means for accomplishing the desired results.

In the conventional pump structure, the end of cylinder 5 opposite hose 4 carries a packing gland through which the plunger extends and normally this gland has the usual hexagon head for screwing it against the packing that is held between the gland and a seat held in place by an annular inwardly directed ridge 10 formed in cylinder 5.

In the present invention, a packing gland 11 is provided, but the head 12 projects flange-like radially outwardly of the sides of cylinder 5 and said head is formed with a radially outwardly opening recess 13 in each of two opposite sides thereof (Fig. 4).

The end of handle 7 that is adjacent the packing gland is reduced in diameter as indicated at 14 and which reduced portion may be tightly held in a metal ferrule 15 having a radially inwardly directed flange 16 that is brazed or otherwise secured to plunger 6.

Concentric with said ferrule 15 and spaced outwardly therefrom but enclosing it, is a cylindrical outer barrel 17 having a radially inwardly directed flange 18 which is rigidly secured to the end of the ferrule 15 that is adjacent the enlarged portion of handle 7. This barrel 17 is spaced outwardly of the said ferrule 15 and an inner barrel 19 substantially co-terminous with the outer barrel is rigidly held in the outer barrel 17 by any suitable means, such as by shrinking the outer barrel on the same.

Before securing the inner barrel 19 to said outer barrel 17, a cylindrical member 20 coaxial with barrel 17 and with ferrule 15 is positioned within the barrel 17 enclosing ferrule 15 which may slidably support the same. A spiral coil spring 21 coaxial with member 20 and surrounding the same reacts between flange 18 and a radially outwardly projecting flange 22 that is formed on member 20 at the outer end of the latter.

The flange 22 is relatively thick and is formed with an annular radially inwardly directed groove or channel within which is secured the peripheral outer edge of a flexible washer 23 that extends radially inwardly from said groove to the plunger 6 and then along the outer sides of said plunger below the radially inwardly facing edge of a flange 24 that projects inwardly from the member 20. A bumper washer 25 alongside washer 23 and facing toward the stuffing box head 12 of the stuffing box 11 is provided for initially engaging an annular ridge 26 on said head 12 when the cylinder 5 and said head 12 are moved toward handle 7.

The end of inner barrel 19 that is opposite flange 18 of the outer barrel is formed with a radially inwardly projecting pair of lugs 27 (Fig. 3) against which the outer side 28 of the flange 22 on member 20 is yieldably held by spring 21. These lugs 27 are formed to pass

through recesses 13 on the head 12 of the packing gland 11 when said recesses and lugs are lined up, thus permitting the head 12 to pass into the outer end of the barrel 19 to a position between lugs 27 and said side 28 of flange 22 against the resistance of spring 21. When the head 12 is in this position, a fractional rotation of the cylinder 5 and handle 7 relatively will bring the head behind the lugs 27 and then upon release of the cylinder 5 or handle, the head 12 will be yieldably held by spring 21 against lugs 27 and said handle and plunger 6 will be locked against movement outwardly of cylinder 5 until the handle or cylinder 5 are so rotated as to bring the lugs 27 to recesses 13 when the plunger and handle will automatically be released from locking relationship for actuation of the plunger for pumping.

As seen in Fig. 5, when the pump cylinder and handle are locked together, there is no projecting latch or other element that might accidentally be caught on some object and actuated. Nor is there any detent, set screw or element separate from the handle and pump cylinder that must first be manipulated before the cylinder and handle can be locked or released. This is important inasmuch as no time is lost in unlocking the cylinder and handle, and the two can be readily unlocked and locked by the operator even while he may be wearing heavy gloves or mittens, and without the necessity of his shifting the device in the hands once it is held in operating position.

It might be said that in operating the pump the handle 7 is usually held in the left hand and the right hand grasps the cylinder 5 adjacent hose 4, upon which relative reciprocation of the plunger and cylinder is effected.

It is to be understood that the specific description of the invention and the drawings is not to be considered restrictive, but is merely illustrative of a preferred form of the invention. The principal result desired is to hold the cylinder and plunger locked together in collapsed position in a safe, simple, rugged, yet quickly releasable manner substantially as described irrespective of how or when the plunger might become accidentally extended. In carrying the pumps on vehicles to and from fires the vibration of the vehicles many times causes extension of the plungers and subsequent injury and inconvenience results.

I claim:

1. In a pump that has a tubular handle, plunger and main cylinder in coaxial alignment with the plunger reciprocable in said cylinder and the handle projecting from one end of the cylinder, the improvement that comprises a cylindrical barrel secured to the end of said handle adjacent said cylinder formed with an open end directed toward said cylinder and projecting toward the latter, a radially outwardly projecting head secured to the end of said cylinder adjacent said barrel, said head being coaxial with said barrel and of a diameter less than that of the barrel adapting it to be enclosed within said barrel at one end of the stroke of said plunger, means within the end of said barrel adjacent said head including a spring urged element positioned for yieldable engagement with said head when the latter is within said barrel for releasably holding said head in said barrel when said plunger is at said one end of said stroke and a member on said barrel against which said head is adapted

to be yieldably urged by said element when said head is in engagement with said element.

2. In a pump that has a tubular handle, plunger and main cylinder in coaxial alignment with the plunger reciprocable in said cylinder and the handle projecting from one end of the cylinder, the improvement that comprises a cylindrical barrel secured to the end of said handle adjacent said cylinder formed with an open end directed toward said cylinder and projecting toward the latter, a packing nut around said plunger secured to the end of said cylinder adjacent said barrel having a radially outwardly projecting head, said head being coaxial with said barrel and of a diameter less than that of the barrel adapting it to be enclosed within said barrel at one end of the stroke of said plunger, means within the end of said barrel adjacent said head including a spring urged element positioned for yieldable engagement with said head when the latter is within said barrel for releasably holding said head in said barrel when said plunger is at said one end of said stroke and a member on said barrel against which said head is adapted to be yieldably urged by said element when said head is in engagement with said element.

3. A lock for releasably securing a tubular pump plunger within a main pump cylinder against accidental withdrawal of the plunger from said cylinder comprising a tubular handle

coaxial with said plunger and cylinder and projecting from one end of the latter, a head secured on said last mentioned end of said cylinder through which said plunger is reciprocable, a cylindrical barrel projecting from said handle toward said cylinder formed with an open end directed toward said cylinder for receiving said head therein, a coil spring in said barrel coaxial therewith and adapted to yieldably engage said head when the latter is in said barrel for tending to force said head out of said barrel, means within said barrel at the end thereof adjacent said cylinder for holding said head in said barrel, said means including spaced lugs adapted to engage said head and said head being formed with recesses adapted to pass said lugs upon rotation of said head and barrel relatively for permitting said head to be withdrawn from said barrel when said lugs and recesses are in registration.
